UNITED STATES PATENT OFFICE.

CHARLES H. WOLFE AND JOHN HEIMLICH, OF PORT CLINTON, OHIO.

NON-EXPLOSIVE TANK.

1,150,089.

Specification of Letters Patent. Patented Aug. 17, 1915.

Application filed March 8, 1913. Serial No. 752,895.

To all whom it may concern:

Be it known that we, CHARLES H. WOLFE and JOHN HEIMLICH, citizens of the United States, residing at Port Clinton, in the county of Ottawa and State of Ohio, have invented certain new and useful Improvements in Non-Explosive Tanks, of which the following is a specification.

Our invention relates to non-explosive tanks and has for its object the provision of an improved non-explosive tank which shall have improved means for protecting its contents from explosion.

With the above and other objects in view, this invention consists substantially in the combination, arrangement and construction of parts all as hereinafter described, shown in the accompanying drawings, which form a part of this specification and illustrate the preferred embodiment of our invention, and more specifically set forth in the subjoined claims.

In the drawings: Figure 1 is a top plan view of our invention; Fig. 2 is a vertical section taken approximately on the line 2—2 of Fig. 1; Fig. 3 is a view of a portion of Fig. 2 showing a different position of the parts; Fig. 4 is a view of a portion of Fig. 2 showing another position of the parts.

Our non-explosive tank is well adapted for containing gasoline, naphtha and other volatile explosive oils.

Heretofore, non-explosive tanks have been constructed with followers for contacting with and covering the surface of the liquid within the tank and such followers have been so loose as to be easily jarred into a position where they would stick between the sides of the tank, thus failing to perform their function of following and allowing the liquid to be drawn from the tank and a considerable amount of air inserted in the tank above the level of the liquid and below the follower. Likewise, these followers have been so constructed that when the tank was carried on a moving vehicle, or stood upon any other moving object adapted to jar it, the follower was forced upward by the moving liquid within the tank and stuck frequently in a position elevated above the normal level of the liquid within the tank, leaving in this manner also an air pocket between the follower and the liquid, even though no liquid had been withdrawn from the tank. We obviate this undesirable feature of non-explosive tanks by providing a

follower supplied with means whereby the follower, as it descends with the upper level of the liquid, is removably locked in that position against upward movement; and furthermore, we so construct our follower that it will not stick in the tank, but will follow the liquid to the bottom thereof.

Other novel features of our construction will appear in the following description.

In the drawings, reference numeral 10 indicates the body portion of our improved tank, the bottom of which is indicated by 11 and the top or rim by 12.

The cover for our tank consists of a hollow float 13, provided with a funnel-shaped aperture 14 for the purpose of gaining access to the interior of the tank. A stopper 15 seals the aperture 14 against the passage of air. The shape and diameter of the float 13 approximate the shape and diameter of the interior of the tank 10. The interior of the hollow float 13 is preferably sealed from communication with the air. Two cupped washers 16 and 17, secured to the float by means of an annular retainer 18, serve to seal the interior of the tank against communication from without, the washer 16 preferably extending downward and the washer 17 extending upward. The retainer 18 bears an upturned peripheral flange 19, which maintains a portion of the washer 17 in contact with the body 10 of the tank. The contact surface between the body 10 of the tank and the washers 17 and 16 is of sufficient depth to prevent any tilting of the float 13 and consequent sticking or jamming of the float in the tank. Ears 20, attached in any suitable manner to the float 13 and preferably at diametrically opposite sides thereof, bear horizontal studs 21, upon which are pivoted slotted handles 22 having outwardly exposed friction surfaces 23 contacting with the inner surface of the body 10 of the tank. The pivot slots of these handles are indicated by reference numeral 24. The upper portion of these handles is preferably pierced, as at 25, to afford ready means for the insertion of the hand of the operator. Formed upon these handles and preferably at the lower end of the friction surface 23 thereof are downwardly extending hooks 26. The horizontal studs 21 engage the slots 24 of the handles and the handles are free to oscillate about the studs in a vertical plane. When, for the purpose of filling the tank or for any other reason,

it is desired to maintain the float 13 at the top of the tank, the handles 22 are grasped by the operator, the float 13 lifted to the top of the tank and the hooks 26 passed over the top or rim 12, as shown in Fig. 3. When the tank is filled, or when it is desired that the float 13 shall contact with the upper surface of the liquid within the tank and descend therewith, the handles are unhooked from the rim 12 and allowed to drop into the position shown in Figs. 1 and 2. In this position the friction surfaces 23 contact with the inner surface of the body 10 of the tank, passing readily down with the float 13 but binding tightly between the body 10 of the tank and the studs 21 when any upward pressure is exerted upon the float 13 other than a direct upward pull upon the handles. Thus, it will be seen that the float 13 while free to descend with the upper surface of the liquid in the tank is prevented from ascending by means of the friction just described. If desired, the handles 22 may be dropped back against the float 13 out of contact with the inner surface of the body of the tank, as shown in Fig. 4. This leaves the float 13 free to ascend or descend.

It should be understood that when the hooks 26 are released from the upper edge of the tank and occupy the positions shown in Fig. 2 the friction surfaces 23 operate automatically to exert a clutching or braking effect on the interior surface of the tank. These automatic friction brakes or clutches may be initially so adjusted as to sufficiently retard any tendency of the float to move upwardly off the liquid in the tank when the latter is swayed about or jarred. But whatever the degree of binding between the surfaces 23 and the interior surface of the tank 10 the clutches or brakes will be readily released whenever the float is free to descend, as when liquid is withdrawn from the discharge opening 29 or from the funnel opening 14. Whenever the rings 25 are grasped by hand and pulled upwardly the friction surfaces 23 will be immediately released and the float 13 can be lifted without being retarded except by the washers 16 and 17 engaging the inner surface of the tank 10. Whenever desired the float 23 may be pushed down on top of the liquid in the tank, which will tend to force the liquid out through the funnel aperture 14, particularly when the stopper 15 is removed. Any suitable device may be substituted for the stoppers 15 when it is desired to withdraw the liquid from the tank 10 by pressing down on the float 13. It should also be observed that our construction is not for the purpose of providing a non-refillable can, but for the purpose of providing a non-explosive tank, including a follower as a cover, which will prevent any air space above the

liquid by the provision of removable or releasable automatic locks, friction brakes or clutches, as described.

Upon the inner surface of the body 10 of the tank, we provide graduations 27, so that when any convenient fixed point upon the float registers with one of them the number of units of liquid remaining in the tank will be indicated.

At 28 is indicated any convenient handle to assist in the removal or insertion of the stopper 15, and at 29 is shown any convenient means for discharging the liquid from the tank, while at 30 is indicated any desirable device for attaching the tank to another object, such as a gasoline stove or a gasoline engine.

In the accompanying drawings and in the foregoing description are set forth the preferred embodiments of our invention, but it is obvious that one skilled in the art may make modifications of the same without departing from the principles of the invention.

We claim:

1. In a non-explosive tank for carrying inflammable fluids, the combination with a container, of a follower floating on the liquid in said tank and sealing its upper surface from the atmosphere, brake mechanism carried by said follower near the periphery thereof and co-acting directly with the inner surface of said container to prevent upward movement of the follower off the surface of said liquid but permitting free descent thereof when liquid is withdrawn from said container, and means for manually releasing said brake mechanism when the follower is lifted prior to re-filling said container.

2. The combination with a container for liquids, of a follower therein, a clutch member provided with a slot, a fulcrum mounted on said follower and engaging said slot, and means for enabling said clutch member to be grasped by hand to release the same.

3. The combination with a container for liquids, of a follower therein, a plurality of friction brake devices each provided with a slot, a plurality of fulcrums mounted on said follower one for each of said slots, a plurality of rings one connected to each of said brake devices to enable the latter to be released manually on the follower being lifted by said fulcrums, and a plurality of hooks, one connected to each of said rings for engaging the upper end of the container to effect the suspension of a follower near the upper end of said container.

4. The combination with a tank for liquids, of a floating follower therein, means for sealing the liquid in a tank from the outside air, a plurality of eccentrically pivoted friction devices mounted on said follower and permitting free descent of said

- floating follower when liquid is discharged from the tank but automatically braking any tendency of the follower to move upwardly.
5. The combination with a container for liquids, of a follower therein, a plurality of friction brakes pivotally mounted on said follower and engaging the inner surface of the container permitting the follower to descend with the top of the liquid but preventing upward movement of the follower through any force exerted on the liquid in the container, said brakes being adapted to be manually disengaged from the container to permit upward movement of the follower.
6. The combination with a container for liquids, of a follower in said container adapted to be supported by liquid in the latter, handles, each having a slot therein, fulcrums mounted on said container and each fulcrum passing through one of said slots providing a pivotal point for one of the handles, there being friction surfaces on the handles adapted to engage the inner side of the container when the fulcrums are at one set of corresponding ends of the slots and permit the follower to descend with the liquid in the container but lock such follower against ascending through any force exerted through the liquid.
7. In a non-explosive tank for containing inflammable fluids, the combination with a container, of a follower capable of floating on the liquid in said container and fitting in said container to seal the upper surface of said liquid from the atmosphere, and brake mechanism carried by said follower and co-acting with the inner surface of said container to prevent upward movement of the follower off the surface of said liquid, but permitting free descent of said follower when liquid is withdrawn from said container.
8. In a non-explosive tank for inflammable fluids, the combination with a container entirely open at one end, a hollow follower capable of floating on liquid in said tank and fitting in said container to seal the liquid in said container from the atmosphere, and a plurality of friction brakes carried by said follower and co-acting with the inner surface of said container to prevent upward movement of said follower, but permitting free descent thereof, said brakes being adapted to be manually released when said follower is lifted to filling position.
9. In a non-explosive tank for inflammable fluids, the combination with a container entirely open at its upper end, of a hollow follower capable of floating on liquid in said container and having a liquid tight connection with the inner surface of said container, brake mechanism mounted on said follower and co-acting with the inner surface of said container to prevent upward movement of said follower when the liquid in the container is jolted but permitting free descent of said follower when the liquid is withdrawn from said container, manually operated means for releasing said brake mechanism and permitting the lifting of said follower, and hooks connected to said manually operated means for engaging the upper edges of said container and holding the follower near the upper end of said container during the filling operation of said container.

In testimony whereof we have signed our names to this specification, in the presence of two subscribing witnesses.
